UNITED STATES PATENT OFFICE

157,231

STRAP FASTENER

Fred W. Andrews, Dover, Del., assignor to International Latex Corporation, Dover, Del., a corporation of Delaware

Application January 3, 1949, Serial No. 37

Term of patent 14 years

(Cl. D17—3)

To all whom it may concern:

Be it known that I, Fred W. Andrews, a citizen of the United States and a resident of Dover, in the county of Kent and State of Delaware, have invented a new, original, and ornamental Design for a Strap Fastener, of which the following is a specification, reference being had to the accompanying drawing, forming part thereof, wherein:

Fig. 1 is a plan view of a strap fastener, showing my new design, the essential features thereof being shown in full lines. The broken line showings are for illustrative purposes only and have been omitted from the disclosure in Fig. 2.

Fig. 2 is a cross-sectional view taken along the line 2—2 of Fig. 1.

I claim:

The ornamental design for a strap fastener, substantially as shown and described.

FRED W. ANDREWS.
